CLAIM

The ornamental design for an agricultural baler, as shown and described.

DESCRIPTION

FIG. 1 is a front perspective view of an agricultural baler showing our new design;

FIG. 2 is a left side view thereof;

FIG. 3 is a right side view thereof;

FIG. 4 is a front end view thereof;

FIG. 5 is a rear end view thereof;

FIG. 6 is a top plan view thereof; and,

FIG. 7 is a bottom plan view thereof.

The broken lines in the drawings are for environmental purposes only and form no part of the claimed design.
